(57) **CLAIM**

The ornamental design for a penis ring, as shown and described.

DESCRIPTION

FIG. 1 is a top perspective view of a first embodiment of a penis ring according to the present design.

FIG. 2 is a front elevation view of the penis ring shown in FIG. 1.

FIG. 3 is a rear elevation view of the penis ring shown in FIG. 1.

FIG. 4 is a top plan view of the penis ring shown in FIG. 1.

FIG. 5 is a bottom plan view of the penis ring shown in FIG. 1.

FIG. 6 is a right side elevation view of the penis ring shown in FIG. 1.

FIG. 7 is a left side elevation view of the penis ring shown in FIG. 1.

FIG. 8 is a top perspective view of a second embodiment of a penis ring according to the present design.

FIG. 9 is a front elevation view of the penis ring shown in FIG. 8.

FIG. 10 is a rear elevation view of the penis ring shown in FIG. 8.

FIG. 11 is a top plan view of the penis ring shown in FIG. 8.

FIG. 12 is a bottom plan view of the penis ring shown in FIG. 8.

FIG. 13 is a right side elevation view of the penis ring shown in FIG. 8.

FIG. 14 is a left side elevation view of the penis ring shown in FIG. 8.

FIG. 15 is a top perspective view of a third embodiment of a penis ring according to the present design.

FIG. 16 is a front elevation view of the penis ring shown in FIG. 15.

FIG. 17 is a rear elevation view of the penis ring shown in FIG. 15.

FIG. 18 is a top plan view of the penis ring shown in FIG. 15.

FIG. 19 is a bottom plan view of the penis ring shown in FIG. 15.

(Continued)

FIG. 20 is a right side elevation view of the penis ring shown in FIG. 15; and,
 FIG. 21 is a left side elevation view of the penis ring shown in FIG. 15.
 The broken lines depict portions of the penis ring that form no part of the claimed design.
